MEANS FOR SUPPLYING FUEL TO FURNACES

Filed Nov. 19. 1921

INVENTOR

Thomas A. Peebles
by Dennis S. Wolcott
Atty.

UNITED STATES PATENT OFFICE.

THOMAS A. PEEBLES, OF PITTSBURGH, PENNSYLVANIA.

MEANS FOR SUPPLYING FUEL TO FURNACES.

Application filed November 19, 1921. Serial No. 516,381.

To all whom it may concern:

Be it known that I, THOMAS A. PEEBLES, residing at Pittsburgh, in the county of Allegheny and State of Pennsylvania, a citizen of the United States, have invented or

discovered certain new and useful Improvements in Means for Supplying Fuel to Furnaces, of which improvements the following is specification,

10 A boiler plant should be designed to meet not only an average steam demand, but also to supply sufficient steam for peak loads, which are frequently two or three hundred per cent of the average load. In some cases 15 these divergent requirements are met by building the plant sufficiently large to meet the maximum demand. But this plan is not desirable as what might be termed the emergency portion of the plant would be idle or 20 non-productive for a large percentage of time.

In some cases, the difficulty has been met by installing stoking mechanism having a capacity considerably in excess of that required 25 for normal operations, and then operating the boilers as high as 400% during peak periods. Such excessively large stoking mechanisms cannot however be operated economically when only an average demand is to be satisfied.

Experience has shown that when the coal fed to a stoker consists of large and small lumps, the operation of the stoking mechanism and the combustion of the coal on the 25 grate bars are more or less irregular. Hence it has become the general practice to crush the coal to lumps substantially uniform in size. In this crushing operation, a very considerable percentage of the coal is pulverized or reduced to such small particles that when mingled with the lumps, it will render the mass comparatively dense, so that the air for combustion will not readily permeate a charge on the grate bars. And further, the pulverized or comminuted material will be immediately consumed on entering the furnace while the lumps will burn more slowly, and hence the generation of heat is irregular.

50 The object of the invention described herein is to effect a segregation of coal dust or pulverized coal from the larger lumps or pieces to utilize the coarser pieces in the normal operation of a boiler and to utilize the pulverized coal or coal dust to supplement the generation due to the combustion of the

coarser coal, at times when the demand for steam is in excess of normal. The invention is hereinafter more fully described and claimed.

60 The accompanying drawing forming a part of this specification, illustrates diagrammatically apparatus adapted to the practice of the invention disclosed herein.

65 In the practice of the invention the coal is fed in any suitable manner to a crushing mechanism 1 of any suitable construction from which the coal is transferred to a suitable stoking mechanism, whereby the coal is fed onto the fuel supporting member in 70 the furnace of a vapor generator. During the movement of the coal from the crushing mechanism to the stoking mechanism, dust or particles of coal of a size or weight below a predetermined maximum are removed 75 from the coal, so that coal fed by the stoker is practically free from finely comminuted coal, which is stored for use in the furnace when the generator is operated above average rating.

80 A convenient apparatus for carrying out the steps outlined consists of a crushing mechanism 1, from which the coal passes through a chute 2 to a conveying mechanism 3 whereby the crushed coal is delivered to a storage bin 4. From this bin the coal is delivered by a spout 5, as required, to the hopper 6 of the stoking mechanism 7. The operation of this stoking mechanism is regulated to supply coal at a rate suitable to 85 maintain a pressure of vapor in the generation required for normal operations.

85 In order to remove from the coal after passing through the crusher, all dust or particles below a predetermined minimum size, the 90 chute 2 is provided with oppositely disposed ports or openings 9, adapted to be connected to suitable means whereby a current of air is caused to flow through the stream of coal passing down the chute and to carry with 95 it coal dust or fine particles of coal. In the construction shown, one of the ports is connected to an exhaust fan 10 which has its outlet connected to a storage bin 11, in which the dust and fine particles of coal are segregated from the air.

100 This storage bin is provided at its lower end with a feeding mechanism 12 of any known construction preferably operated by a constant speed motor 13. The pulverized coal is delivered to a pipe 14 extending to the furnace of the generator, and through

which the coal is forced by a current of air induced by a steam jet 15. It is preferred that the air flowing through the pipe 14 should not only serve to move the coal to the furnace, but should be sufficient or nearly sufficient in quantity for the combustion of the pulverized coal. As it is the usual practice to supply air somewhat in excess of that required for the combustion of the coal fed by the stoking mechanism, such excess will be available to supplement air entering with the pulverized coal, or what air in addition to that entering with the fuel, is required, may be admitted through a port or ports in the wall of the furnace.

In the operation of a boiler plant embodying the improvement described herein, fuel for operating at normal rating will be supplied by the stokers. On an increase of load, the attendant will start the motor of the feed mechanism 12 and open the valve controlling the flow of steam to the injector nozzle 15. As the feeding mechanism 12 is adjusted to so supplement the stoker feed, that the boiler may be operated up to the maximum rating, the amount of fuel fed may at times exceed the requirement. In such case, the stoking mechanism will be automatically adjusted to feed less coal.

It is characteristic of the improvement claimed herein that in the practice of the invention, coal, free from dust, is fed by the stoker and that by utilizing the pulverized coal and dust to operate the boiler above normal rating, the employment of excessively large stoking mechanism is avoided, and the employment of a plant larger than necessary to supply steam for average loads is rendered unnecessary.

It should be understood that the element

1 is merely a crushing device for reducing large lumps to a size in which they can be conveniently fed to a furnace by stoking mechanism.

I claim herein as my invention:

1. In a steam generating plant, the combination of means for crushing coal to lumps of approximately uniform size, means for removing the pulverized or fine particles from the lumps of the crushed mass, a furnace, a stoking mechanism for feeding the cleaned lumps to the furnace, means for conveying cleaned lumps from the crushing means to the stoker, and means independent of the stoking mechanism for feeding the dust of pulverized particles removed from the crushed mass to said furnace. 45 50 55

2. In a steam generating plant, the combination of means for crushing coal to lumps of approximately uniform size, a storage bin, means for removing the dust or fine particles from the crushed mass to the place of storage, a furnace, a stoking mechanism for said furnace, means for carrying the lumps from the crushing and segregating means to the stoker and means for conveying the fine particles of pulverized material from the bin to said furnace. 60 65 70

3. In a plant for generating steam, the combination of means for segregating pulverized coal or dust from lumps, a storage bin for the reception of coal dust, a furnace, a stoker for said furnace, means for conducting the lumps free of dust from the crushing and segregating means to the stoker and means for feeding the coal dust from the storage bin to the said furnace. 75

In testimony whereof, I have hereunto set my hand.

THOMAS A. PEEBLES.
